(57) **CLAIM**

The ornamental design for a reagent cartridge, as shown and described.

DESCRIPTION

FIG. 1 is a top perspective view of a reagent cartridge showing the removable sealing layers attached, according to our new design;

FIG. 2 is a bottom perspective view thereof;

FIG. 3 is a top plan view thereof;

FIG. 4 is a bottom plan view thereof;

FIG. 5 is a right elevation thereof;

FIG. 6 is a left side elevation view thereof;

FIG. 7 is a first end view thereof;

FIG. 8 is a second end view thereof;

FIG. 9 is a top perspective view of a reagent cartridge showing the removable sealing layers detached;

FIG. 10 is a bottom perspective view thereof;

FIG. 11 is a top plan view thereof;

FIG. 12 is a bottom plan view thereof;

FIG. 13 is a right elevation thereof;

FIG. 14 is a left side elevation view thereof;

FIG. 15 is a first end view thereof; and,

FIG. 16 is a second end view thereof.
